SLIDE FASTENERS

Frederick Ulrich, Jersey City, N.J., assignor to Commar Products Corporation, Newark, N.J., a corporation of New Jersey

Application December 3, 1952, Serial No. 323,754

17 Claims. (Cl. 24—205.15)

The invention relates to improvements in slide fasteners of the type comprising a pair of stringers, each formed of tape having spaced, interlockable fastener elements secured thereto, the fastener elements being engaged or disengaged by a slider acting to open and close the fastener.

There are times, due either to the improper application of a slide fastener to a garment, or because of the presence of an undergarment in the path of a slider, that the material of the garment or undergarment becomes caught or snagged between the fastener elements, or between the fastener elements and the slider. It then becomes desirable to be able to simply and quickly release the snagged material without ripping or otherwise damaging the fabric. One answer to this problem is provided by the invention disclosed in the application of Albert Bashover, Serial Number 337,786, filed February 19, 1953, having the same assignee as the present invention.

As disclosed in said co-pending case, the slider wings are permanently and fixedly connected to each other, so that one of the most critical dimensions of the slider, namely, the height of the internal Y-shaped channel, is maintained substantially fixed and constant. The slider wings are rigidly connected to each other in the same manner as in the ordinary or non-releasing type of slider. The slider wings are formed to provide enlarged tape slots, too large to enable the slider to laterally retain the fastener elements. In practical form, the wings are made without flanges. A separate movable or retractable member having inturned flanges is disposed upon the slider body, so that when the member is in its down or normal fastener operating position, the inturned flanges are positioned over the enlarged tape slots. These flanges laterally confine or retain the fastener elements, and permit the slider to interlockably engage the fastener elements as the slider is moved to close the fastener. When the flange-providing member is retracted, the tape slots of the body are opened up, and the slider will no longer retain the fastener elements. This permits the fastener elements to be moved laterally outward from between the wings and through the enlarged tape slot, thereby allowing the stringers and slider to be separated.

When the user of a garment having such a slide fastener opens up the slider to release a snagged piece of material, the slider is completely separated from both stringers. Complete separation of the slider from both stringers increases the likelihood of losing the slider. A principal object of the present invention is to overcome this difficulty, and to provide a slider which is constructed to release snagged material and yet which is retained upon one stringer of the fastener even after the slider has been opened. It might be anticipated that opening a slider to release one stringer would release material snagged on that side only of the slider, but contrary to all expectation I have found that the operation will also release material snagged on the opposite side of the slider, that is, material snagged against the

2

stringer on which the slider is retained. The explanation for this is set forth later.

The present invention may be employed while retaining the most important advantage of the slider disclosed in the aforesaid application of Albert Bashover, namely, the provision of a pair of spaced wings which are rigidly connected to each other in fixed relationship by means of a post formed therebetween at one end of the slider in the same manner that it is in conventional sliders.

10 In accordance with my invention the wings of the slider body are formed so that one side only will laterally retain a stringer, the other side being formed with an enlarged tape slot too large to retain a stringer. In simplest practical form one side of the slider body is flanged, while the other side is made without flanges. A member having an inturned flange on that side of the slider body having the enlarged tape slot is connected to the slider body and made movable with respect thereto. For normal fastener operation the inturned flange of the member is positioned over the enlarged tape slot and permits the slider to interlockably engage the fastener elements.

20 In the stringer-releasing position of the member, the enlarged tape slot of the body is opened up to the extent that a stringer may escape from the slider, permitting the stringers to be stripped apart and to release any material which may have become snagged.

25 The described construction of the slider which furnishes the snag-releasing function while preventing removal of the slider from the fastener also has been found to be particularly useful for another application in the art of slide fasteners, namely, for fasteners of the quick disassembly type. Since the slider itself is 30 constructed to release a stringer while remaining connected to the other stringer, it is now possible to provide a quick disassembly slide fastener of either the fully separable or non-separable type without necessitating a releasing end stop, dissimilar stringer lengths, or special bottom or top assemblies, such as have heretofore characterized such quick disassembly slide fasteners. The slider itself constitutes the entire mechanism for realizing the quick assembly action, with the remaining components of the fastener, the top and bottom stops and the stringers being of properly selected though common and inexpensive type. It will be understood that the quick disassembly fastener here described is also a snag-releasing fastener.

35 Another object of the invention is to provide improved and simplified means for releasably locking the flange-providing member on the slider body, thereby simplifying the manipulation required by the user of the fastener in changing the slider from its normal fastener operating condition to the condition where the fastener will release a stringer, whether to release material or for quick disassembly.

40 A further object of the invention is to simplify the construction of the flange-providing member and its assembly with the slider body, thereby reducing the cost of manufacturing the product.

45 To accomplish the foregoing objects, and other more specific objects which will hereinafter appear, my invention relates to the elements of the slider and their novel relation to one another, and the novel combination of the slider with its stringers as are hereinafter more particularly described in the following specification, and sought to be defined in the claims. The specification is accompanied by drawings in which:

50 Fig. 1 is a plan view of one form of a slider made in accordance with the present invention;

55 Fig. 1A is a perspective view of a preferred form of flange-providing member;

Fig. 2 is a side elevation of a slider in condition for normal fastener operation;

Fig. 3 is a vertical cross-section taken approximately in the plane of line 3—3 of Fig. 1;

Fig. 4 is a view similar to Fig. 2 showing the relationship of the parts of the slider when it is desired to release snagged material or to quickly disassemble a fastener of which the slider is a component;

Fig. 5 is a view similar to Fig. 3 showing the flange-providing member retracted to enable releasing of snagged material, or quick disassembly of a fastener;

Fig. 6 is a partial plan view of a slide fastener provided with a slider of the present invention, preparatory to releasing the snagged material;

Fig. 7 is a view similar to Fig. 6 showing, on an enlarged scale, the relative positions of the components of a slide fastener when extraneous material has become snagged between the fastener elements and the slider of the present invention, this view omitting the top wing and the flange-providing member of the slider for the purpose of clarity in illustration;

Figs. 8 and 9 are views similar to Figs. 6 and 7, respectively, illustrating how snagged material may be released with a slider made in accordance with the present invention;

Figs. 10 and 11 are views similar to Fig. 3 showing two other embodiments of the invention;

Fig. 12 is a plan view of a quick disassembly slide fastener of the non-separable type made in accordance with the present invention;

Fig. 13 is a partial plan view of the fastener of Fig. 12 with the slider in position preparatory to reassembling the disassembled stringers;

Fig. 14 is an enlarged end view showing the relationship of the slider and the bottom stop preparatory to reassembling the stringers of the non-separable quick disassembly fastener;

Fig. 15 is a view similar to Fig. 14 showing the slider in condition for normal fastener operation;

Fig. 16 is a plan view of the fastener after the slider has been moved up from the bottom stop to reassemble the stringers; and

Fig. 17 is a plan view of a quick disassembly slide fastener of the fully separable type.

In all forms of the invention shown, the slider includes a slider body B and a flange-providing member F mounted upon one of the wings of the slider body. The flange-providing member is connected to the slider body in a manner to permit the member to be moved or retracted with respect to the slider body and to prevent their complete separation.

The slider body comprises top and bottom wings w, w' permanently connected to each other at their upper ends by a neck or post n in fixed, spaced relationship. Preferably, the wings w, w' and the post n are integrally formed. However, the wings may be welded or riveted together at their upper or neck end in strong, permanent, fixed, spaced relationship. The slider body may be made in accordance with usual manufacturing practices, such as by stamping, rolling, die-casting, or molding, and may be made of any suitable metal or plastic composition. The slider body B, however, is formed along only one side with means for laterally retaining a stringer or the fastener elements. Preferably such means constitutes an integrally formed inturned flange on either one of the wings, or on both wings on the same side of the slider body, thereby providing a tape slot T of a size which does not permit fastener elements to pass therethrough, and preventing the slider from being removed from the adjacent stringer. On the other side of the slider body a tape slot T' is provided which is too large to laterally retain the fastener elements of the other stringer for interlockable engagement. On this side of the slider body, the inturned flanges are omitted from both wings. Thus, the wings w, w' and post n provide the surfaces of the slider's

internal Y-shaped channel necessary to confine the fastener elements on both stringers to engage or disengage them except for one longitudinal side of the channel which is open and will permit the fastener elements of the adjacent stringer to escape.

As shown in Fig. 3, when the flange-providing member F is in its down or normal fastener operating position, the size of the enlarged tape slot T' is reduced by the positioning of its inturned flange immediately outside the ends of the jaws of the fastener elements so that together with the inturned flange or flanges provided by the slider body on the opposite side the fastener elements on both stringers are laterally retained to permit the slider to interlockably engage or disengage them as the fastener is closed or opened. In effect, the movable flange provides the surface for completing the internal Y-shaped channel of the slider. When the member F is retracted the fastener elements of the stringer adjacent the tape slot T' are permitted to escape, the slider being retained on the opposite stringer of the fastener, however, by the flange or flanges on the opposite side of the slider body. As will herein-after appear, this non-removability does not interfere with the slider's ability to release material which may become snagged even on that side of the slider having the fixed inturned flange or flanges.

As is common in the art, the top wing w is provided with a lug L to support means to permit the user to move the slider along the fastener. In the illustrated slider, this is a finger piece or pull device P of the pendant type, and it will be understood that it may take various forms. The lug L preferably is formed integrally with the top wing w, but, if desired, a separately formed lug may be secured to the slider body B. The lug L is laterally indented in the usual fashion to provide laterally extending flanges 20 beneath which are received a pair of trunnions 22 oppositely disposed and extending from the arms 24 formed at one end of the pull P. To accommodate the added thickness of the member F, the lug L is made high enough to accommodate the thickness of both the member F and the thickness of the trunnions 22.

The member F is best shown in Fig. 1A. It is preferably formed as a stamping from sheet metal having resilient or spring-like qualities, and is provided with an inturned flange f of sufficient height and length so that when the member F is in its down position or normal fastener operating position, the slider is provided with an inturned flange positioned over the tape slot T' to retain the fastener elements for interlockable engagement.

As shown in Figs. 6 to 9, and Figs. 12, 13, 16 and 17, a typical fastener is represented by a pair of stringers S, S' comprising tapes having spaced interlockable fastener elements e with jaws j securing them to the tapes. In the form of the invention shown in Figs. 1 to 5, the slider body B is provided with but one inturned flange 26 formed integrally with the bottom wing w'. In the form of the invention shown in Fig. 10, the slider body is also provided with only one inturned flange 28, formed, however, to extend from the top wing w. In the form of the invention shown in Fig. 11, the wings w and w' are each formed with a single inturned flange 30 and 32, respectively. In each embodiment of slider shown, the slider body flange or flanges are located adjacent the tape slot T and serve their usual function of retaining the fastener elements of the adjacent stringer for interlockable engagement, and together with the flange f of the member F located over the enlarged tape slot T', retain the fastener elements of both stringers for normal fastener operation.

When it is desired to release any material or fabric which may have become snagged between the fastener elements, or the fastener elements and the slider, the member F is moved from the position shown in Figs. 2 and 3 to the position shown in Figs. 4 and 5. As shown in greater detail in Figs. 5 to 9, with the member F in retracted position, the fastener elements e on the stringer S'

may be moved or peeled out through the enlarged tape slot T'. Simply stripping the stringers S and S' apart is usually sufficient to release any material which may have become snagged. Where, as shown in Fig. 7, a segment of undergarment material, designated M, becomes snagged between the forward ends of the fastener elements e and the post n of the slider, on that side of the slider which has the fixed flange or flanges, the removal of the stringer S' through the tape slot T', as shown in Fig. 8, permits unsnagging of even this troublesome type of snag. As shown in Fig. 9, when the slider no longer confines the fastener elements of both stringers, the slider is retained on the stringer S loosely. The fastener elements on this stringer may freely move across the entire width of the slider's internal channel in the stem or at the mouth end to a position passing through the opposite side of the slider, but are prevented from escaping from the slider in a lateral direction by the presence of the body flange or flanges on one side and the slider post n on the other side. As a result of the free rotation of the slider, the space between the post n of the slider and the forward ends of the elements e may be enlarged, permitting the slider to be moved away from the intervening material M and thereby releasing the same.

The slider and the stringer S may then easily be reassembled with the removed stringer S'. This is accomplished by simply moving the slider down to the bottom stop of the fastener (or to that point below the slider where the fastener elements are still in interlocked engagement of the fastener or still partially meshed), adjusting the position of the slider, returning the member F to its down or normal fastener operating position with the flange f positioned immediately outside the ends of the jaws j of the fastener elements e on the stringer S', the position shown diagrammatically in Fig. 3.

Figs. 12 and 16 illustrate the invention as applied to a quick disassembly fastener of the non-separable type. Except for the slider, the fastener is of the common variety, and comprises the usual stringers S, the top stops t, and the bottom stop A which permanently connects the stringers together and limits the movement of the slider. As is common practice in the art, the bottom stop A comprises a pair of substantially parallel plates a, a' connected together at one end by a neck portion b. The plates a and a' are clamped onto the edges of both stringer tapes and the overall width of the stop is substantially equal to the width of the engaged elements e on both stringers. With an ordinary slider, bottom stop A would be received in the lower or stem portion of the slider's internal Y-shaped channel when the fastener is completely opened or with the slider in the position shown in Fig. 13. The stringers, however, could not be disassembled at the top of the fastener as desired in a quick disassembly fastener. By providing the fastener with a slider of the construction shown in Figs. 1 to 5, or Fig. 10, or Fig. 11, this ordinary fastener is converted to one which may be quickly disassembled, with the added advantage that it may be quickly disassembled anywhere along the length of the fastener, instead of at the top end only.

As shown in Fig. 12, a fastener including a slider made in accordance with the present invention may be quickly disassembled by retracting the member F, whereupon the stringer S may be peeled out of the slider by the application of a cross-pull force to the fastener at or above the slider. The stringers may be stripped apart down to the bottom stop A, the bottom stop being received between the wings w, w' of the slider in the stem portion of the internal channel, as shown in Figs. 13 and 14. When the member F is moved from the open position shown in Fig. 14 to normal fastener operating position shown in Fig. 15, the slider may be moved up to close the fastener, as shown in Fig. 16.

It will be readily apparent that a fastener of the fully separable type, as shown in Fig. 17, and which includes

5 a fully separable bottom assembly, designated C, may be quickly disassembled anywhere along the length of the fastener by means of the slider of the present invention, without requiring the use of a releasing end stop, a special top stop, or dissimilar lengths of stringers, such as have heretofore been used for quick disassembly slide fasteners.

Although no bottom stop has been shown in Figs. 1 through 10 of the drawing, it may be mentioned here that the bottom stop may be either one of the types shown in Figs. 12 and 17. If the slide fastener which is to be made snag-releasing is of the non-separable type, the bottom stop may be like that shown in Fig. 12. It may be any bottom stop of the now conventional type in which the bottom stop is dimensioned small enough to be received within the lower end of the slider. If the fastener which is to be made snag releasing is used on a garment or other device which opens fully, the bottom stop used will be one of the known fully-separable bottom stops, for example, one in which one stringer carries a socket, such as that shown at 60 in Fig. 17, while the other stringer carries a pin, such as that shown at 62, the said pin being dimensioned to be received at its lower end in the socket 60.

25 In connection with the improved construction of the flange-providing member F and its relationship with the slider body B and the pull device P, as shown in Figs. 1 and 2, the member F is preferably made to fit like a cap over the slider wing w. As shown in Fig. 1A, the member F is formed to a contour substantially the same as the shape in plan view of a slider wing. It is preferably made of spring metal, for example, Phosphor bronze, and is provided with a window 34 through which the lug L extends.

30 35 As shown in Figs. 1A to 5, the lower longitudinal side edges of the member F are provided with bent-down portions 36, 36' each having a height substantially equal to the thickness of the wing w plus the desired height of the flange f. The member F preferably is made with the 40 two bent-down portions 36, 36' (although only one flange is needed) in order to make the member symmetrical in transverse cross-section and to balance the releasable locking means which is about to be described. The second bent-down portion 36' also provides a flange portion f' which aids in laterally retaining the fastener elements when the member F is in normal fastener operating position. The distance between the bent-down portions 36, 36' is substantially equal to the width of the adjoining wing w except that the extremities, the flanges f and f' are indented, thereby providing the sloping shoulders 38 and 38', as best shown in Figs. 1A, 3 and 5. The distance between the inside surfaces of the flanges f and f' is made to equal the desired width of the slider channel.

50 55 As shown in Fig. 3, the sloping shoulders 38, 38' releasably hook under the edges of the wing w. The top longitudinal edges of the wing w are formed with bevels 40, 40' to facilitate snapping the member F over the wing and releasably lock the member in down position. These bevels need extend for only the length of the stem portion of the wing w, as is best shown in Fig. 4.

60 65 Similarly the indentation of the sides 36, 36' of the member F need extend for only the stem portion of the slider and may terminate where the slider diverges, as indicated at 64, 64' in Fig. 1A and Fig. 4. Thus the detent action which locks the member F in operative position takes place at the stem portion of the slider. The flanges extend further in diverging relation to the point 43.

70 75 The upper portion of the member F, designated 42, which is located above the lug of the slider, and at the neck end of the slider, is bent upwardly at an angle of approximately thirty (30) degrees, and is made so that its extremity 44 will extend no higher than, and preferably below, the top of the lug L when the member F

is in the normal fastener operating position shown in Fig. 2. Thus, a pressing iron will engage the lug before it will engage the upturned end of the member F.

The member F is assembled with the slider body B by simply placing it on top of the wing w, with the lug L extending through the window 34. The pull device P is then attached to the lug by bringing the arms 24 into parallelism, whereupon the trunnions 22 will bear on top of the member F and prevent its separation from the slider body.

With the components of the slider assembled as described, and with the snap-lock means comprising the shoulders 38, 38' hooked beneath the bottom edges of the wing w, as shown in Figs. 2 and 3, the member F is moved to snap-releasing or stringer-releasing position by swinging the pull P around its pivotal connection to the lug L until it bears against the edge 44 of the upwardly inclined portion 42. By pressing downwardly upon the pull device in the direction of the arrow, as indicated in Fig. 4, the resilient connection between the member F and the wing w at the other end of the slider is broken, thereby lifting the bent-down portions 36, 36' above the tape slots T and T'. From another viewpoint it may be said that the bent-down portions 36 and 36' extend along the slider a distance such as to clear the tape slot when raised, the termination being indicated at 43 in Figs. 2 and 4.

The upwardly inclined portion 42 is preferably itself provided with a downturned edge or peripheral wall 45. This has the advantage of stiffening the portion 42, and of providing a smooth rounded finish for the top of the slider assembly. It will be noted that the bottom edge, designated 46, of the upwardly inclined peripheral wall 45, is angularly related to the slider body, and that it is narrow, so that when the member F is tilted to the open position (Fig. 4), no part thereof obstructs the open tape slot T'. Furthermore, it will be noted that the top edge 44 of the member F is so located that when the pull device P engages it, the position of the pull device is beyond the range it normally assumes to open and close the fastener. In normal operation of a slide fastener the user does not turn the pull upwardly and around further than the dotted line indicated in Fig. 2 at x-x.

Where, as shown in Figs. 10 and 11, the slider body B is provided with an inturned flange extending from the body wing w, the balance or symmetry of the snap-lock forces may be maintained by providing the member F with a bent-down portion 48 which is indented to provide a projection 50 adapted to be received within a pocket 52 in the wing w. In this manner, the flange-providing member F is prevented from canting to one side, and the movable flange f is maintained in desired position for normal fastener opening or closing.

It will be apparent that the structure of the flange-providing member, and its relationship to the slider body and pull device as shown in Figs. 1-5, whereby the member may be simply and effectively releasably locked in position, is also suitable for the removable slider disclosed in the aforesaid pending application of Albert Bashover.

The slider of the present invention may be of the non-locking type or the locking type. As shown, for example, in Fig. 12, this slider may be made of the pin-lock variety, in which case it is only necessary to provide a window 54 in the member F as well as the underlying wing of the slider body, through which a pin 56 on the pull device P may pass to engage fastener elements in the internal channel of the slider.

It will be apparent that while I have shown and described my invention in several preferred forms, changes may be made in the structures shown without departing from the spirit of the invention as sought to be defined in the following claims.

I claim:

1. A slider for slide fasteners of the type comprising a

pair of stringers, each of said stringers being formed of tape having spaced, interlockable fastener elements secured thereto, said slider comprising a body having a pair of spaced wings of substantially the same dimensions connected to each other at one end by a post in fixed relationship, said wings being so formed that only one side of the body will laterally retain a stringer, both wings being flangeless at the other side of the body to provide an enlarged tape slot which is too large to laterally retain a stringer, and a member additional to the slider body having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said enlarged tape slot to the extent that a stringer may escape from the slider.

2. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, said wings on one side of the body both being flangeless and providing an enlarged tape slot which is too large to laterally retain a stringer, an inturned flange provided on at least one of the wings on the opposite side of said body to laterally retain a stringer, and a member additional to the slider body having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position acting to open up said enlarged tape slot to the extent that the stringer may escape from the slider.

3. A slider for slide fasteners of the type comprising a pair of stringers, each of said stringers being formed of tape having spaced, interlockable fastener elements secured thereto, said slider comprising a body having spaced top and bottom wings of substantially the same dimensions connected to each other at one end by a post in fixed relationship, said wings on one side of the body both being flangeless and providing an enlarged tape slot which is too large to laterally retain a stringer, an inturned flange provided on the bottom wing on the opposite side of said body to laterally retain a stringer, and a member additional to the slider body having a pair of inturned flanges, said member being movable in a direction transverse to the flat faces of the tapes and wings from a stringer-retaining to a stringer-releasing position, said member in its stringer-retaining position acting to position an inturned flange over the enlarged tape slot and permitting the slider to interlockably engage the fastener elements, and in its stringer-releasing position acting to open up said enlarged tape slot to the extent that the stringer may escape from the slider.

4. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, both of said wings being flangeless at one side of said body so that at least one side of the body is provided with an enlarged tape slot which is too large to laterally retain a stringer, a member additional to the slider body having an inturned flange, said member being movable

ble in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said enlarged tape slot to the extent that a stringer may escape from the slider, and snap-lock means comprising resilient portions of said member engaging opposite side edges of an adjacent wing for releasably retaining said member in stringer-retaining position.

5. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, both of said wings being flangeless at one side of said body so that at least one side of the body is provided with an enlarged tape slot which is too large to laterally retain a stringer, a member additional to the slider body having an inturned flange, said member being movable from a stringer-retaining to a stringer-releasing position, said member having an upwardly inclined portion at the post end of the slider, and snap-lock means for releasably retaining said member in stringer-retaining position, in which position the size of the enlarged tape slot is reduced by the positioning of the inturned flange over said slot to permit the slider to interlockably engage the fastener elements, said member being movable to stringer-releasing position to open up said tape slot to the extent that a stringer may escape from the slider by pressing against said inclined portion to overcome the retaining force of said snap-lock means.

6. A slider for slide fasteners of the type comprising a pair of stringers, each of said stringers being formed of tape having spaced, interlockable fastener elements secured thereto, said slider comprising a body having a pair of spaced wings connected to each other at one end by a post in fixed relationship, a lug on one of said wings, said wings being so formed that at least one side of the body is provided with an enlarged tape slot which is too large to laterally retain a stringer, a member having an inturned flange, said member being movable from a stringer-retaining to a stringer-releasing position, said member having an upwardly inclined portion starting at the lug and going toward the post end of the slider, a pull device secured to said lug, said pull device securing said member to said body, and snap-lock means for releasably retaining said member in stringer-retaining position, in which position the size of the enlarged tape slot is reduced by the positioning of the inturned flange over said slot to permit the slider to interlockably engage the fastener elements, said member being movable to stringer-releasing position to open up said tape slot to the extent that a stringer may escape from the slider by pressing said pull device against said inclined portion to overcome the retaining force of said snap-lock means.

7. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, said wings being so formed that at least one side of the body is provided with an enlarged tape slot which is too large to laterally retain a stringer, a member having an inturned flange, said member being movable from a stringer-retaining to a stringer-releasing position, said member having an upwardly inclined portion at the post end of the slider, a pull device secured to said body, said pull device securing said member to said body, and snap-lock means for releasably retaining said member in stringer-retaining position, in which posi-

tion the size of the enlarged tape slot is reduced by the positioning of the inturned flange over said slot to permit the slider to interlockably engage the fastener elements, said snap-lock means comprising resilient portions of said member engaging opposite side edges of an adjacent wing, said member being movable to slider-releasing position to open up the tape slot to the extent that a stringer may escape from the slider by pressing said pull device against said inclined portion to overcome the retaining force of said snap-lock means.

8. A slider for slide fasteners of the type comprising a pair of stringers, each of said stringers being formed of tape having spaced, interlockable fastener elements secured thereto, said slider comprising a body having a pair of spaced wings connected to each other at one end by a post in fixed relationship, a lug on one of said wings, said wings being so formed that at least one side of the body is provided with an enlarged tape slot which is too large to laterally retain a stringer, a member having an inturned flange, said member being movable from a stringer-retaining to a stringer-releasing position, said member having an upwardly inclined portion starting at the lug and going toward the post end of the slider, a window in said member, said lug extending through said window, a pull device secured to said lug and securing said member to said body, and snap-lock means for releasably retaining said member in stringer-retaining position, in which position the size of the enlarged tape slot is reduced by the positioning of the inturned flange over said slot to permit the slider to interlockably engage the fastener elements, said snap-lock means comprising resilient portions of said member engaging opposite side edges of an adjacent wing of said body, said member being movable to slider-releasing position to open up the tape slot to the extent that a stringer may escape from the slider by pressing said pull device against said inclined portion to overcome the retaining force of said snap-lock means.

9. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, said wings being so formed that only one side of the body will laterally retain a stringer, both wings being flangeless at the other side of the body to provide an enlarged tape slot which is too large to laterally retain a stringer, a member additional to the slider body having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said enlarged tape slot to the extent that a stringer may escape from the slider, and snap-lock means comprising resilient portions of said member engaging opposite side edges of an adjacent wing for releasably retaining said member in stringer-retaining position.

10. A slider for slide fasteners of the type comprising a pair of stringers, each of said stringers being formed of tape having spaced, interlockable fastener elements secured thereto, said slider comprising a body having a pair of spaced wings connected to each other at one end by a post in fixed relationship, the space between said wings on one side of the body providing an enlarged tape slot which is too large to laterally retain a stringer, an inturned flange provided on at least one of the wings on the opposite side of said body to laterally retain a stringer, a member having an inturned flange on that side of the slider body having the enlarged tape slot,

said member being movable from a stringer-retaining to a stringer-releasing position, said member having an upwardly inclined portion starting at the middle region of the slider and going toward the post end of the slider, and snap-lock means for releasably retaining said member in stringer-retaining position, in which position the size of the enlarged tape slot is reduced by the positioning of the inturned flange over said slot to permit the slider to interlockably engage the fastener elements, said member being movable to stringer-releasing position to open up said tape slot to the extent that a stringer may escape from the slider by pressing against said inclined portion to overcome the retaining force of said snap-lock means.

11. A slider for slide fasteners of the type comprising a pair of stringers, each of said stringers being formed of tape having spaced, interlockable fastener elements secured thereto, said slider comprising a body having a pair of spaced wings of substantially the same dimensions connected to each other at one end by a post in fixed relationship, the space between said wings on one side of the body providing an enlarged tape slot which is too large to laterally retain a stringer, an inturned flange provided on at least one of the wings on the opposite side of said body to laterally retain a stringer, a member having an inturned flange on that side of the slider body having the enlarged tape slot, said member being movable from a stringer-retaining to a stringer-releasing position, said member having an upwardly inclined portion at the post end of the slider, a pull device secured to said body, said pull device securing said member to said body, and snap-lock means for releasably retaining said member in stringer-retaining position, in which position the size of the enlarged tape slot is reduced by the positioning of the inturned flange over said slot to permit the slider to interlockably engage the fastener elements, said member being movable to stringer-releasing position to open up said tape slot to the extent that a stringer may escape from the slider by pressing said pull device against said inclined portion to overcome the retaining force of said snap-lock means.

12. A slider for slide fasteners of the type comprising a pair of stringers, each of said stringers being formed of tape having spaced, interlockable fastener elements secured thereto, said slider comprising a body having a pair of spaced wings connected to each other at one end by a post in fixed relationship, a lug on one of said wings, the space between said wings on one side of the body providing an enlarged tape slot which is too large to laterally retain a stringer, an inturned flange provided on at least one of the wings on the opposite side of said body to laterally retain a stringer, and a member having an inturned flange on that side of the slider body having the enlarged tape slot, said member being movable from a stringer-retaining to a stringer-releasing position, said member having an upwardly inclined portion starting at the lug and going toward the post end of the slider, a pull device secured to said lug, said pull device securing said member to said body, and snap-lock means for releasably retaining said member in stringer-retaining position in which position the size of the enlarged tape slot is reduced by the positioning of the inturned flange over said slot to permit the slider to interlockably engage the fastener elements, said snap-lock means comprising resilient portions of said member engaging opposite side edges of an adjacent wing, said member being movable to slider-releasing position to open up the tape slot to the extent that a stringer may escape from the slider by pressing said pull device against said inclined portion to overcome the retaining force of said snap-lock means.

13. A snag-releasing, non-removable slider for slide fasteners of the type comprising a pair of stringers, each of said stringers being formed of tape having spaced,

interlockable fastener elements secured thereto, said slider comprising a body having a pair of spaced wings of substantially the same dimensions connected to each other at one end by a post in fixed relationship, said wings and post providing the surfaces of the internal Y-shaped channel required to confine the fastener elements on both stringers to engage or disengage them except for one longitudinal side of the channel which is open laterally for its full width and will permit the fastener elements of one stringer to escape, and a member additional to the slider body having an inturned flange providing a surface for completing the internal Y-shaped channel, said member being movable in a direction transverse to the flat faces of the tapes and wings from a position to confine the fastener elements on both stringers for interlockable engagement to a position where the fastener elements of one stringer may escape, said slider then being very loosely retained on the other stringer alone whereby any material which may have become snagged between the slider and the fastener elements of either stringer may be released.

14. A slider for a quick disassembly slide fastener comprising a pair of stringers, each of said stringers being formed of tape having spaced, interlockable fastener elements secured thereto, said slider being so constructed that it will in itself, without the provision of a releasing end stop or dissimilar lengths of stringers or special top or bottom stops, release one of the stringers and be retained on the other stringer when it is desired to quickly disassemble the fastener, said slider comprising a body having a pair of spaced wings of substantially the same dimensions connected to each other at one end by a post in fixed relationship, said wings being so formed that only one side of the body will laterally retain a stringer, both wings being flangeless at the other side of the body to provide an enlarged tape slot which is too large to laterally retain a stringer, and a member additional to the slider body having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said enlarged tape slot to the extent that the adjacent stringer may escape, said slider being retained by the other stringer.

15. A slider for a quick disassembly slide fastener comprising a pair of stringers, each of said stringers being formed of tape having spaced, interlockable fastener elements secured thereto, said slider being so constructed that it will in itself, without the provision of a releasing end stop or dissimilar lengths of stringers or special top or bottom stops, release one of the stringers and be retained on the other stringer when it is desired to quickly disassemble the fastener, said slider comprising a body having a pair of spaced wings of substantially the same dimensions connected to each other at one end by a post in fixed relationship, said wings on one side of the body both being flangeless and providing an enlarged tape slot which is too large to laterally retain a stringer, an inturned flange provided on at least one of the wings on the opposite side of said body to laterally retain a stringer, and a member additional to the slider body having an inturned flange on that side of the slider body having the enlarged tape slot, said member being movable in a direction transverse to the flat faces of the tapes and wings from a stringer-retaining to the stringer-releasing position, said member in its stringer-retaining position acting to position the inturned flange over the enlarged tape slot and permitting the slider to interlockably engage the fastener elements,

and in its stringer-releasing position opening up said enlarged tape slot to the extent that the adjacent stringer may escape, said slider being retained by the other stringer.

16. A slider for a quick disassembly slide fastener of the non-separable type comprising a pair of stringers, each of said stringers being formed of tape having spaced, interlockable fastener elements secured thereto, a non-separable bottom stop of the ordinary type permanently securing the stringers together, said slider being so constructed that it will in itself, without the provision of a releasing end stop or dissimilar lengths of stringers or special top stops, release one of the stringers and be retained on the other stringer when it is desired to quickly disassemble the fastener, said slider comprising a body having a pair of spaced wings of substantially the same dimensions connected to each other at one end by a post in fixed relationship, said wings being so formed that only one side of the body will laterally retain a stringer, both wings being flangeless at the other side of the body to provide an enlarged tape slot which is too large to laterally retain a stringer, and a member having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said tape slot to release the adjacent stringer, said slider being retained by the other stringer whereupon by returning said slider to said bottom stop and moving said member to stringer-retaining position both stringers may be reassembled by the slider.

17. A slider for a quick disassembly slide fastener of the non-separable type comprising a pair of stringers, each of said stringers being formed of tape having spaced, interlockable fastener elements secured thereto, a slider having an internal Y-shaped channel, and a non-separable bottom stop of the ordinary type permanently securing the stringers together, said stop being dimensioned to be

received within the stem portion of the slider's internal Y-shaped channel, said slider comprising a body having a pair of spaced wings of substantially the same dimensions connected to each other at one end by a post in fixed relationship, said wings on one side of the body both being flangeless and providing an enlarged tape slot which is too large to laterally retain a stringer, an inturned flange provided on at least one of the wings on the opposite side of the body to laterally retain a stringer, and a member additional to the slider body having an inturned flange on that side of the slider body having the enlarged tape slot, said member being movable in a direction transverse to the flat faces of the tapes and wings from a stringer-retaining to a stringer-releasing position, said member in its stringer-retaining position acting to position the inturned flange over the enlarged tape slot and permitting the slider to interlockably engage the fastener elements, and in its stringer-releasing position opening up said tape slot to release the adjacent stringer, said slider being retained by the other stringer, whereupon by returning said slider to and over said bottom stop and moving said member to stringer-retaining position both stringers may be reassembled by the slider.
